UNITED STATES PATENT OFFICE.

TALBOT G. MARTIN, OF CHICAGO, ILLINOIS, ASSIGNOR TO AUTOMATIC ELECTRIC COMPANY, OF CHICAGO, ILLINOIS, A CORPORATION OF ILLINOIS.

MEASURED-SERVICE TELEPHONE SYSTEM.

Original application filed May 15, 1919, Serial No. 297,332. Patent No. 1,459,229, dated June 19, 1923.
Divided and this application filed December 4, 1922. Serial No. 604,755.

To all whom it may concern:

Be it known that I, TALBOT G. MARTIN, a citizen of the United States of America, and a resident of Chicago, Cook County, and 5 State of Illinois, have invented certain new and useful Improvements in Measured-Service Telephone Systems, of which the following is a specification.

The present invention relates in general 10 to measured service telephone systems, but is concerned more particularly with improved circuits and devices for manually controlling a paystation or coin collector in such a system; and the object of the invention 15 is to provide means for operating a coin collector of the coin first type, when calls are made by an operator through an automatic switch, to an automatic subscriber's line which is provided with a coin collector of the above type.

This application is a division of an application bearing Serial No. 297,332, filed May 15, 1919, which eventuated in Patent No. 1,459,229, June 19, 1923.

Referring to the drawings, Fig. 1 shows 25 a manual calling line, and an operator's cord circuit adapted for use in answering and completing calls initiated by such lines. Fig. 2 shows a connector switch which is 30 accessible to a cord circuit such as shown in Fig. 1, and is used to complete connections to any of a number of called lines such as line A.

Referring now particularly to Fig. 1, the 35 calling manual station B is of the usual type, its line conductors terminating in the usual answering jack, with which is associated the line signal 81 controlled by the usual line and cut off relays. The cord circuit F is of the usual type used by an 40 operator of a semi-automatic system in extending connections to automatic substations, the circuits having been modified to take care of certain new features which will 45 be described in the detailed description which is to follow.

Referring now to Fig. 2, the connector H' 50 is of the well known Strowger type, and is accessible to the cord circuit F for extending connections initiated by manual lines such as B to any of the automatic lines such as A. The substation A is of the usual type used in modern automatic telephone systems, and

is equipped with a coin collecting device of the coin first type. 55

It is understood that any standard type of coin collector or paystation device, such as that shown in U. S. Letters Patent No. 1,043,219 granted November 5, 1912, to O. F. Forsberg, may be used with this invention 60 which is adapted to receive a coin deposited before a call is initiated and having a chute for returning the coin if the call is unsuccessful, and for collecting the coin if the call is successful. I have only shown the 65 circuits of the collector used as my invention has to do principally with the circuits and method of controlling the collecting and refunding.

In order to clearly describe the invention, 70 the manner of extending a connection from a manual to an automatic subscriber will be described. For this purpose it will be assumed that a subscriber at B wishes to extend a connection to the automatic substation A, and it will further be assumed 75 that the subscriber at B desires to have the charge reversed.

When the subscriber B lifts the receiver 80 the operator is signaled in the usual manner by means of the lamp 81 which is extinguished when the operator inserts the plug into the jack of the calling line, the operator then throws her listening key, obtains 85 the wanted number and inserts the calling plug P into a jack such as J leading to an idle connector switch such as H' (Fig. 2) which has access to the multiple normals of the line A. The line relay 82 of the connector H' is energized in series with the 90 coil 80 of the cord circuit and the lamp 84 of the cord circuit is lighted through the springs 85 of relay 86. The operator then throws her calling device key to bridge the calling device 87 across the cord circuit in 95 series with the line relay 82. Relay 82 closes the circuit of relay 88 which prepares the circuit of slow relay 89 and vertical magnet 90 and closes the springs 91, 92 and 93 into contact. When the calling device is operated 100 for the first digit of the called number the line relay 82 operates to close the circuit of magnet 90 and relay 89 in series to step the wipers of the switch to the desired level of the bank. Soon after the impulses of this 105

the circuit of slow relay 94 and rotary magnet 95 in multiple, and when relay 82 is operated for the next digit of the called number magnet 95 operates to step the wipers 5 of the switch H' into engagement with the normals 96, 97 and 98 of the line A. Relay 94 remains energized for a short time after the rotary impulses cease to hold the private wiper in connection with the busy relay 99 10 so that if the called line is busy the relay 99 will operate to connect a busy tone to the operator. If the line is idle however, the relay 94 upon falling back, closes a circuit for the upper winding of relay 100 from 15 ground at springs 91 and 92, through said winding and through relay 22 and magnet 21 of the called line to battery. Relay 100 energizes and locks energized to cut the called line through to the ringing circuit 20 and ring cut off relay 101. When the called subscriber answers relay 101 energizes and completes the circuit of the back bridge relay 86, which also energizes in series with the called line to open the springs 85 to extinguish the lamp 84 to inform the operator 25 that the called man has answered.

The special relay 102 in series with the line relay is a polarized relay which does not operate with the usual battery potential, 30 but only with a battery of 110 volts of either polarity. Now, when the called subscriber answers and the operator finds that the right party has answered the operator first informs him that the calling party has asked 35 to have the charges reversed and requests him to drop a coin of the proper denomination for the call. The called subscriber deposits the coin and the operator then throws her key 103 to energize the relay 104, connecting the positive high voltage battery 105 40 out over the trunk line and through relay 102 to ground. Relay 82 is held energized and relay 102 operates to attract its armature in such a direction as to close the springs 45 to connect the high voltage battery 108 out over the lower talking conductor to conductor 97 through springs 7 of the calling device of station A, springs 11 and 10, springs 17 and 18, and magnet 13 to ground, thus 50 depositing the coin. The operator then restores the talking circuit and allows the two subscribers to converse in the usual manner.

Should the operator be unable to get the calling party after the called man has deposited the coin or for any other reason desire to refund the coin after it is deposited by the called man she may throw the key 110 to connect the reversed high voltage battery to relay 120 which in turn projects 55 negative high voltage battery to the coin collect magnet of the called line to operate said magnet in a direction to refund the charge.

In some instances the manual subscriber 60 may not desire that the charge be reversed, 65 in which case the operator will charge the

calling subscriber for the call in a manner well known in manual practice.

It will be seen, therefore, that I have provided a very efficient means for manually controlling a coin collector of the coin first 70 type in a semi-automatic system.

Having fully described and ascertained the features and aspects of the invention, what is considered to be new and is desired to have protected by Letters Patent will be 75 pointed out in the appended claims.

What I claim is:

1. In a telephone system, a line, a pay-station for the line, an automatic switch for seizing said line, an operator having access 80 to said switch and having means for controlling the switch to seize the line, a magnet for the pay-station for either refunding or collecting the coin, and means in the switch controlled by the operator for operating said magnet to collect or refund the coin. 85

2. In a telephone system, a line, a pay-station for the line, an automatic switch for seizing said line, an operator having access 90 to said switch, and having means for controlling the switch to seize the line, a polarized magnet for the pay-station for either refunding or collecting the coin, said magnet non-responsive to normal current in the line circuit, and means in said switch controlled by the operator for connecting either 95 a positive or negative high potential current source to said magnet to collect the coin in one case and to refund the coin in another case. 100

3. In a telephone system, a calling and a called line, an operator's switchboard, means whereby the operator can establish a talking circuit between said lines, said means including an automatic progressively movable 105 switch between said operator's switchboard and the called line, paystation mechanism at the station on the called line, and means controlled by the operator over said talking circuit for collecting or refunding coins deposited in said paystation. 110

4. In a telephone system, a calling and a called line, an operator's switchboard, means whereby the operator can establish a talking circuit between said lines, said means including an automatic progressively movable switch, an inductive connection included in said talking circuit between said switchboard and said called line, paystation mechanism at the station on the called line, said 120 mechanism responsive to high voltage currents applied to the talking circuit at the said switchboard to collect or refund deposited coins, and means for relaying such currents past said inductive connection to 125 control said paystation as set forth.

5. In a telephone system, lines, paystations thereon having charge assessing means, an automatic progressively movable switch, an operator's switchboard, means including said 130

switch for setting up a talking connection from said switchboard to a desired one of said lines, and means controlled from said switchboard and over said talking connection for operating the charge assessing means at the paystation on the connected line.

6. In a telephone system, lines, each having a coin collect and refund paystation thereon, an operator's switchboard, an automatic progressively movable switch, means for setting up a connection from said switchboard to a desired one of said lines, said connection including said switch, and means controlled from said switchboard through said switch to selectively control the paystation on the selected line to either collect or refund a coin deposited therein.

7. In a telephone system, a line having a coin collect and refund paystation thereon, an operator's switchboard, an automatic progressively movable switch, means for setting up a connection through said switch from said switchboard to said line, and means

controlled from said switchboard for applying currents of different characters to said connection at said switch to operate said paystation to collect or refund a coin deposited therein.

8. In a telephone system, subscribers' lines, a paystation on each of said lines, an operator's switchboard, means including an automatic operator controlled numerical switch for selecting a desired one of said lines and extending a talking connection thereto, said connection comprising two inductively connected sections, current sources of different characters, and means controlled by the operator at said switchboard for connecting one or the other of said sources to the second section of the talking circuit to collect or refund a coin deposited in said paystation.

In witness whereof, I hereunto subscribe my name this 1st day of December, A. D. 1922.

TALBOT G. MARTIN.
